UNITED STATES PATENT OFFICE.

WILLIAM LESTER HANSEN, OF PRINCETON, INDIANA.

COMPOUND MAGNET.

1,292,460.

Specification of Letters Patent. Patented Jan. 28, 1919.

Application filed November 19, 1917. Serial No. 202,804.

To all whom it may concern:

Be it known that I, WILLIAM LESTER HANSEN, a citizen of the United States, residing at Princeton, in the county of Gibson and State of Indiana, have invented certain new and useful Improvements in Compound Magnets; and I do declare the following to be a full, clear, and exact description of the invention such as will enable others skilled in the art to which it appertains, to make and use the same.

This invention relates to certain new and useful improvements in magnets.

The primary object of the invention is to provide a magnet of maximum efficiency by providing a structure in which an electro-magnet is coupled to a permanent magnet in such a manner as to act, when deenergized, as a bridge bar or keeper for the permanent magnet and thus to form a closed magnetic circuit; and, when energized, to work in combination with the permanent magnet so that the total flux of the magnet structure is the flux of the electro-magnet added to that of the permanent magnet.

Another object of the invention is to provide a device of this character which will be comparatively simple, strong, durable and inexpensive in construction, efficient and reliable in operation and well adapted to the purpose for which it is designed.

With these and other objects in view, the invention consists of certain novel features of construction, and the combination and arrangement of parts as will be hereinafter fully described and claimed.

In the accompanying drawings forming a part of the application:

Figure 1 is an elevation of one side of a magnet constructed in accordance with this invention;

Fig. 2 is an elevation of the other side of the magnet;

Fig. 3 is an edge view of the magnet;

Fig. 4 is an end view of the same;

Fig. 5 is an elevation of one side of another form of magnet constructed in accordance with this invention;

Fig. 6 is an end view of the modified form;

Fig. 7 is an edge view of the same; and

Fig. 8 is a detail sectional view taken on the plane indicated by the line 8—8 of Fig. 5.

In the embodiment illustrated in Figs. 1 to 4 of the drawings, the numeral 1 designates a permanent U shaped magnet which is preferably formed of a plurality of U

shaped sections 2 arranged one within another and being spaced a short distance apart. The sections 2 are of magnetized hardened steel and are in effect individual permanent magnets but they act as one permanent magnet inasmuch as their like poles are disposed adjacent one another and are coupled or connected together by means of soft iron pieces or bars 3 and bolts 4, the soft iron pieces or bars 3 extending transversely across the ends of the sections 2 with their ends projecting beyond the edges of the latter and provided with alined openings to receive said bolts 4. The outermost and innermost pieces or bars 3 contact with the outer sides of the outer and inner sections 2, while the intermediate pieces or bars are disposed between the adjacent sections 2.

The numeral 5 designates an electro-magnet, to the ends of the soft iron core 6 of which are screwed or otherwise fastened, soft iron bars 7, the latter having their free ends contacting with and connected to one of the projecting ends of the bars 3, preferably by means of the bolts 4 which extend through these ends. The core 6 being thus connected to the poles of the permanent magnet, it acts as a bridge bar or keeper for the same and thus forms a closed magnet circuit by reason of which little or no free magnetism or magnetic attraction is manifested at the extreme ends of the magnet 1.

When the device is to be used, an electric current is supplied to the electro-magnet 5, the current being passed through said magnet 5 in the proper direction to cause its core 6 to be magnetized and thus to form magnetic poles at its end, these poles being of the same polarity as the poles of the permanent magnet 1. Thus the electro-magnet 5, when energized, acts in combination with the permanent magnet 1 so that the total flux of the magnet structure is the flux of the electro-magnet plus that of the permanent magnet. In other words, the balance of the closed magnetic circuit is disturbed by the magnet 5, so that the core 6 of the latter no longer acts as a bridge bar or keeper, but acts as another magnet, added to the permanent magnet. When the circuit through the magnet 5 is broken, the magnetic balance is restored, and the core 6 again acts as a keeper.

In Figs. 5 to 8 of the drawings the same principle is shown worked in a magnet structure, to the permanent magnet 1' of which

two electro-magnets 5' and 5'' are connected. The ends of the sections 2' of the magnet 1' are clamped together by means of soft iron bars 3' and bolts 4', and between the ends of 5 these bars 3' are soft iron plates 7' which assist the cores 6' and 6'' of the magnets 5' and 5'' in forming a closed magnetic circuit for the permanent magnet. The two magnets 5' and 5'' are wound and connected in 10 such a way as to magnetize the ends of their cores 6' and 6'' to correspond to the polarity of the ends of the magnet 1. The modified form just described acts similar to the manner in which the first form described 15 acts, and hence repetition is unnecessary.

From the foregoing description, taken in connection with the accompanying drawings, the construction, use and operation of the invention will be readily understood with- 20 out a more extended explanation.

As various changes in form, proportion, and in the minor details of construction may be resorted to without departing from the spirit of the invention, it is to be under- 25 stood that I do not wish to be limited to the construction herein shown and described other than as claimed.

I claim:-

1. A device of the character described 30 comprising a U shaped permanent magnet, soft iron bars, an electro-magnet, and means coöoperative with said soft iron bars for clamping the ends of said permanent magnet and securing said electro-magnet 35 thereto.

2. A device of the class described comprising a U shaped permanent magnet composed of a plurality of U shaped sections arranged one within another and spaced a 40 short distance apart, soft iron bars extending transversely across the ends of said sections and having their ends projecting beyond the side edges thereof, the outermost and innermost bars contacting with the outer

and inner sides of the outer and inner sec- 45 tions, and the intermediate bars being dis- posed between the adjacent sections to hold the latter in their spaced relation, clamping bolts extending through the ends of said bars, and an electro-magnet having its core 50 connected to said bars to form a closed mag- netic circuit for the permanent magnet when deënergized, said electro-magnet when en- ergized magnetizing the ends of its core to 55 correspond to the polarity of the adjacent ends of the permanent magnet.

3. A device of the class described com- 60 prising a U shaped permanent magnet com- posed of a plurality of U shaped sections ar- ranged one within another and spaced a short distance apart, soft iron bars extend- 65 ing transversely across the ends of said sec- tions and having their ends projecting be- yond the side edges thereof, the outermost and innermost bars contacting with the outer and inner sides of the outer and inner sec- 70 tions, and the intermediate bars being dis- posed between the adjacent sections to hold the latter in their spaced relation, clamping bolts extending through the ends of said bars, additional bars disposed between one of the ends of the fixed mentioned bars, fastened to the same and extending laterally therefrom, and an electro-magnet having its core connected to the last mentioned bars 75 to form a closed magnetic circuit for the permanent magnet when deënergized, said elec- tro-magnet when energized magnetizing the ends of its core to correspond to the polarity of the ends of the permanent magnet. 80

In testimony whereof I have hereunto set my hand in the presence of two subscribing witnesses.

WILLIAM LESTER HANSEN.
